UNITED STATES PATENT OFFICE.

JOHN R. FISHER AND LEANDER T. FISHER, OF KNOBNOSTER, ASSIGNORS TO THEMSELVES, AND JOHN C. WINKLER, ALPHEUS P. WINKLER, CHAUNCEY COBB, GORDON HARDEY, AND ARTHUR E. VEST, ALL OF JOHNSON COUNTY, MISSOURI.

DUPLEX PROPELLER-PUMP.

SPECIFICATION forming part of Letters Patent No. 338,148, dated March 16, 1886.

Application filed May 9, 1885. Serial No. 164,994. (No model.)

To all whom it may concern:

Be it known that we, JOHN R. FISHER and LEANDER T. FISHER, citizens of the United States, residing at Knobnoster, in the county 5 of Johnson and State of Missouri, have invented certain new and useful Improvements in Duplex Propeller-Pumps; and we do hereby declare that the following is a full, clear, and exact description of the invention, which will 10 enable others skilled in the art to which it appertains to make and use the same.

This invention relates to that class of propeller-pumps which embody channeled sections forming chambers in which propeller-wheels 15 rotate, the series of wheels being carried by a longitudinal rotary shaft.

The object of our invention is to provide a simple and improved duplex pump of this class, which will be so balanced that the machine-friction usual in propeller-pumps is reduced, and which will furthermore possess advantages in point of inexpensiveness, durability, power, and capacity.

In the drawings, Figure 1 is a longitudinal sectional view of our improved duplex pump. Fig. 2 is a detail perspective view of one of the channeled sections, parts being broken away to show the propeller-wheel. Fig. 3 is a detail sectional view showing the manner of 25 connecting the sections of the cylinder. Fig. 4 is a detail elevation of the outer face of one of the propeller-wheels. Fig. 5 is a detail elevation of the inner face of one of the propeller-wheels. Fig. 6 is a detail transverse sectional view of one of the propeller-wheels, and Fig. 7 is a longitudinal vertical sectional view 30 of the bed.

Corresponding parts in the figures are denoted by the same letters of reference.

Referring to the drawings, A designates the base or bed, upon which the cylinder of our improved pump is mounted in horizontal position, upright standards B B being provided at each end of the base, and having boxes b b, 40 forming the bearings for the longitudinal rotary shaft which carries the propeller-wheels, a pulley, C, being provided upon the shaft near one end, by which power is transmitted to drive the pump. From this arrangement

it is manifest the pump may be used as a power-pump, or that the engine may be attached directly to the shaft.

The cylinder D comprises a central section, E, forming the suction-chamber, from which extends the suction-pipe F² to an inlet, I². The portions of the cylinder at each side of this chamber are formed by a series of sections, G, each formed with a wheel-chamber, g, in one end, and having a series of channels, g², extending from the wheel-chamber and contracted toward their other end, as shown, so that the mouths of the channels are larger at the wheel-chamber than at the other end of the section. At each end of the cylinder is provided a section, H, forming a discharge-chamber, into which enter suitable discharge-pipes, I, which unite through pipes I⁴ to a single outlet. At the outer ends of these discharge chambers or sections H are provided suitable stuffing-boxes, J J, through which the longitudinal shaft passes.

The various sections comprised in the cylinder of the pump are connected together by means of the following arrangement: The sections G are each provided with a circumferential shoulder, g³, formed in the edge of the channeled portions of said sections, which shoulders receive the edge g⁴ of the wheel-chamber portions of the sections, as plainly illustrated in Fig. 3, when the sections are set together. The central section, E, is provided with circumferential shoulders e at its ends, which receive the edge g⁴ of the adjoining sections G, and the end sections, H H, are provided with annular projections or flanges h², which are received by the shoulder g³ of the adjoining sections G. By this construction a lap-joint is formed between the sections, and these joints are preferably ground in the manufacture of the pump to secure a water-tight connection when the sections are set together. The sections are secured in position by means of a series of rods, K, passing through annular flanges h³, respectively, upon the ends of the end sections and the central section, these rods being disposed longitudinally and nutted, as shown at k, or otherwise secured.

L designates the propeller-wheels, which

comprise a hub, l , from which projects the disk or flange l^2 , forming the body of the wheel. This disk has disposed around its periphery a single spiral plate or flange, l^3 , the edge of which is surrounded by a cylindrical ring or rim, the width of which is about equal to that of the disk l^2 . The flange l^3 forms an inclined plane, which, when revolved in the proper direction, projects the water through the channels g^2 , the water being received by the wheel at the point designated by l^4 , where the face of the flange l^3 is even with the outer end of the hub, and is projected through the inclined channel to the point designated by l^5 , where the face of the disk is even with the inner end of the hub, from whence it is discharged through the channels. The points l^4 and l^5 are opposite, and the flange is connected at this point, as shown at l^6 . A propeller-wheel is disposed in the wheel-chamber of each section G, the wheels in the sections at different sides of the central section, E, being, respectively, arranged in right and left position, so that the water is projected from the center toward the ends of the cylinder. The longitudinal shaft M passes through the sections of the cylinder and through the hubs of the wheels, and carries the latter in its revolutions, the wheels being locked to the shaft by a set-screw, N, as shown; or we may use a longitudinal key. The wheels are secured against longitudinal displacement upon the shaft by making the hub P of such a length that the end will rest against the face of the next propeller-wheel. This construction gives additional strength to the wheel. The shaft is provided with a sleeve or collar, p, at about its center in the suction-chamber of the cylinder, against which shoulder the end of the first propeller of the series rests.

The boxes for the propeller-shafts may be made adjustable longitudinally, and for this purpose the shaft is grooved at b' , into which fit corresponding projections in the boxes b. These boxes b are made movable upon their seats on the tops of the standards B, and can be held in any position to which they are adjusted by means of set-screws b^2 b^3 in the flanges B' B' on the standards. The operation and advantages of our invention will be readily understood by those skilled in the art to which it appertains. The water is taken at the center through the suction-pipe F² into the suction-chamber, from whence it passes into the first propeller-wheel, and is forced by the propeller-wheels toward the end discharge-chambers. The propeller-wheels on different sides of the suction-chamber being arranged in right and left position, the water is of course forced and discharges into both chambers.

By this improved arrangement of duplex pump, the machine-friction consequent upon heavy lifts is reduced, as the reaction at one end of the cylinder counteracts that at the other end.

In order to point out more clearly the scope

of our invention, we would have it understood that we do not seek to claim anything shown in the patent of Moorehouse, No. 195,630, dated September 25, 1877.

We do not wish to be understood as limiting ourselves to the exact construction and arrangement of parts as herein shown and specified, as it is manifest that numerous modifications may be made without departing from the spirit and scope of our invention. For instance, the number of sections G may be increased or diminished, according to quantity of water to be handled, and the height to which it is desired to raise it.

We claim as our invention and desire to secure by Letters Patent—

1. In a duplex propeller-pump, the combination of the cylinder comprising the central suction-chamber, the series of sections having channels g^2 disposed at each side of the suction-chamber, and forming wheel-chambers, the discharge-chambers at the ends of the cylinder uniting in a single outlet, the bed upon which the cylinder is mounted having two channels connected with the outlet-chambers at the ends of the cylinder uniting in one outlet from said bed, said bed being also provided with a channel communicating with the inlet or suction chamber, the longitudinal rotary shaft, and the herein-described propeller-wheels secured upon the shaft, substantially as and for the purpose set forth.

2. In a duplex propeller-pump, the combination of the cylinder comprising the central suction or inlet chamber, the series of sections having channels g^2 disposed at each side of said suction or inlet chamber, and forming wheel-chambers, and the discharge-chambers at the ends of the cylinder, the bed upon which the cylinder is mounted having two channels connected with the outlet-chambers at the ends of the cylinder uniting into one outlet from said bed, said bed being also provided with a channel communicating with the inlet or suction chamber, as set forth.

3. The combination of the central chamber or section having the projecting flange e^3 and shoulder e, the series of sections at each side the latter having channels aligning with each other, and each provided with a wheel-chamber and a circumferential shoulder in the edge of their channeled portions, which shoulders receive the projecting edges of the wheel-chamber of the adjoining section, the end chambers having the channeled inner portions, and provided with the flanges h^2 and h^3 , and the longitudinal rods passing through and secured to the flanges h^3 , substantially as shown and described.

In testimony whereof we affix our signatures in presence of two witnesses.

JOHN R. FISHER.
LEANDER T. FISHER.
